UNITED STATES PATENT OFFICE

2,387,421

DRIVE FOR PAPER MANUFACTURING MACHINES

Alfred Vanden Bergh, Green Bay, Wis.

Application February 28, 1944, Serial No. 524,275

1 Claim. (Cl. 74—55)

This invention relates generally to drives for paper manufacturing machines, and more particularly to pulp screening apparatus.

My present invention is especially designed as an improvement in the construction shown in Letters Patent No. 2,323,168 issued to me on June 29, 1943.

The primary object of my present invention is to provide a drive of the character specified, in which the initial cost and maintenance will be considerably less than any other now in use.

A further object of my invention is to provide an improved drive of the character specified that will be smoother in operation, and whereby greater production may be attained since greater speed will not damage the parts in any way.

With the foregoing and other objects in view that will appear as the nature of my invention is better understood, the same consists in the novel features of construction, combination and arrangement of parts illustrated in the accompanying drawings and more particularly pointed out in the appended claim.

In the accompanying drawings, which are for illustrative purposes only and are therefore not drawn to scale:

Figure 1 is a fragmentary side elevation, illustrating my present improvements.

Figure 2 is a vertical sectional view, taken on line 2—2 of Figure 1, looking in the direction indicated by the arrows.

Figure 3 is a similar view, taken on line 3—3 of Figure 2, and Figure 4 is a horizontal section, taken on line 4—4 of Figure 2.

Referring to the drawings for a more particular description of my invention, and in which drawings like parts are designated by like reference characters throughout the several views, the numeral 1 represents the customary vat of a pulp screen, provided with the usual diaphragm 2. Drive units making up the present invention and designated by the reference numeral 3, are situated under the vat 1, and each drive unit consists of a box-like structure, comprising the U-shaped frame 4, consisting of the upright legs 5 and transverse connecting bottom 6. The frame 4 further comprises a bridge piece 7 at the top, connecting the upper ends of the legs 5 and extending through the aforesaid bridge piece, is a guide bushing 8 through which the vertical connecting rod 9 is slideable. The box is further provided with the side panels 10, suitably secured to the frame 4, and a drive shaft 11 extends through the lower portions of the panels of each drive.

In carrying out my present invention, the lower end of the vertical connecting rod 9, has a direct threaded connection, as at 12, with the center of the horizontal guide bar 13. The guide bar 13 comprises the central semi-circular portion 14, in which is mounted the circular roller 15, and the opposite end portions 16 mounted to slide up and down on the perpendicular rods 17. The lower ends 18 of the rods 17 are threaded in suitable blocks 19 situated at the bottom of the frame 4. 5 A cam 20, preferably formed at its edge with four corresponding straight flat inclined faces 21, separated by the minor arcuate or rounded segments 22, is fixed to the shaft 11, within the frame 4 of each drive unit, and works against the edge of 10 the circular roller 15, the purpose of which will presently appear. Coil compression springs 23 are disposed around the upper ends of the perpendicular rods 17 between the upper faces of the end portions of the guide bar 13, and the lower ends of the cylindrical sleeves. The sleeves 24 extend through corresponding openings 25 in the top member 7 of the frame 4 and are held in place by the lock nuts 26, screwing on the upper threaded ends of the rods 17.

20 In practice, when the drive shaft 11 rotates, the diaphragm 6 is caused to raise and lower to actuate the pulp in the vat 5, by means of the cam 20, roller 15, guide bar 13, connecting rod 9 and compression springs 23.

30 Among the many advantages derived through the use of my improvements, some of the more important may be briefly enumerated as follows:

First: The initial cost and subsequent maintenance of my improved cam drive is considerably less than any others now in use.

Second: The drive operates smoother and imparts perfect up and down movement to the diaphragm, without loss of motion or danger of tearing the rubber diaphragm.

Third: More production may be attained, as greater speed will not result in damage to any of the parts.

Fourth: Wear and friction of cams and rollers is reduced to the minimum.

Fifth: The construction is simplified and all bolts on the inside of the frame or housing, are eliminated.

50 From the foregoing description taken in connection with the drawings, it is thought that the construction, operation and advantages of my present improvements will be understood, without requiring a more extended explanation.

55 Various changes in the form, proportions and minor details of construction may be resorted to

without departing from the principles or sacrificing any of the advantages of my invention, as defined in the appended claim.

Having described my invention, what I claim as new and desire to secure by Letters Patent is:

In combination with the diaphragm of a pulp screening apparatus used in paper manufacturing machines, a horizontal drive shaft, a frame through which the drive shaft operates, a cam mounted on the drive shaft, within said frame, a horizontal guide bar, comprising a central semi-circular portion or housing and straight horizontal end portions, a circular roller of a diameter

substantially equal to that of the cam, mounted in the central semi-circular housing of the guide bar and working against the edge of the cam, a vertical endwise movable rod, connected at its lower end to the central housing of the guide bar and movable with the latter, perpendicular guide rods for the straight horizontal end portions of the guide bar, cylindrical sleeves extending through the top member of the frame, and coil compression springs disposed around the upper ends of said perpendicular guide rods between said sleeves and the end portions of the guide bar.

ALFRED VANDEN BERGH.
